DICTATING MACHINE

Hugo Hendrik Maria Vananderoye, Hasselt, Belgium, assignor, by mesne assignments, to U.S. Philips Corporation, New York, N.Y., a corporation of Delaware

Filed June 12, 1967, Ser. No. 7,448

Claims priority, application Spain Feb. 3, 1967

Term of patent 14 years

Int. Cl. D14—01

U.S. Cl. D26—14

Fig. 1

Fig. 2

FIG. 1 is a perspective view of the dictating machine illustrating my design, showing the rear microphone support in extended position.

FIG. 2 is another perspective view of the dictating machine showing the rear microphone support in retracted position and the front microphone rest removed for ease of illustration.

The dominant features reside in the solid line portions.

I claim:

The ornamental design for a dictating machine, as shown and described.
